UNITED STATES PATENT OFFICE.

HARRY I. ILLINGWORTH, OF SWAMPSOFT, MASSACHUSETTS, ASSIGNOR TO BOSTON MACHINE WORKS COMPANY, OF LYNN, MASSACHUSETTS, A CORPORATION OF MASSACHUSETTS.

ROTARY CEMENTING AND SNIPPING MACHINE.

No. 878,959.

Specification of Letters Patent.

Patented Feb. 11, 1908.

Application filed December 20, 1906. Serial No. 348,678.

To all whom it may concern:

Be it known that I, HARRY I. ILLINGWORTH, a citizen of the United States, residing at Swampscott, in the county of Essex and State of Massachusetts, have invented an Improvement in Rotary Cementing and Snipping Machines, of which the following description, in connection with the accompanying drawings, is a specification, like letters on the drawings representing like parts.

My invention is particularly intended for simultaneously cementing and snipping shoe uppers, but is adapted for general use wherever it is desired to snip or cut at intervals during the application of cement in a strip or other local area.

My present invention relates to that type of machine set forth at length in my co-pending application Ser. No. 348,677, where I have particularly claimed certain of the generic features common to both machines.

My present mechanism proceeds upon the principle of feeding the stock and applying the cement step by step and providing snipping mechanism co-operating with the cement-applying mechanism, said snipping mechanism being under the control of the operator and being actuated in the intervals of rest of said intermittently operating, feeding and cementing mechanisms. By this means not only is the machine more simple in its construction and operation, but the work accomplished is extremely accurate and certain and it is capable of being run at a higher speed with greater general efficiency.

In the accompanying drawings I have shown a preferred embodiment of my invention.

Figure 1 is a view in side elevation, partly broken away; Fig. 2 is a front elevation partly broken away; Fig. 3 is a horizontal sectional view through the base of the machine, showing the operating shaft and mechanism; Fig. 4 is an enlarged perspective view of the periphery of the cement applying wheel, showing its cellular structure; Figs. 5 and 6 are fragmentary views in front elevation and transverse section respectively, of the mechanism for giving the desired step-by-step movement.

From any suitable base 1 extends an over-

hanging arm 2 in which is journaled an upper shaft 3 and a lower shaft 4 positively driven in unison by like gears 5, 6. At the outer end of the shaft 3 is a cement-applying wheel 7 receiving cement from the delivering mouth 8 of a cement tank 9 and delivering the cement to work interposed at 10 between said cement wheel and a feed roll 11 mounted fast on the outer end of the shaft 4, the latter shaft having its journal pivoted at 12 in the overhanging arm 2 and its outer end pivotally supported at 13 on a post 14 held in yielding sliding position by a spring 15 in a bearing 16 in the frame.

The construction above described and its general operation are substantially the same as more fully set forth in my above-mentioned copending application, although, as there stated, I do not intend to restrict myself to the structural details herein set forth unless otherwise required by certain of the more specific claims. The post 14 has a stop 17 at its lower end co-operating with a stop cam 18 rotated by an arm 19 with relation to a gage 20 on the front of the machine whereby the nearness to which the wheel 7 and roll 11 can approach is positively controlled, although they may yield apart to any extent required by unevenness of stock fed through the machine.

In my before-mentioned application the cementing and snipping movements take place without any halting of the machine, said movements and the feeding of the stock proceeding simultaneously and continuously, but I have found that superior results can be secured by halting the mechanism for the snipping operation and that by arranging the halting mechanism so that it is exceedingly short in duration and so that the feeding and halting take place in such quick succession as to be almost imperceptible, not only can greater accuracy of work be secured and less wear of the machine result therefrom, but higher speed and general efficiency of the machine may be accomplished. This rapid and yet absolutely positive step-by-step movement is secured in the present preferred embodiment of my invention by providing a transverse shaft 21 having fast thereon a special wormlike wheel

22 coöperating with a spur gear wheel 23 on the shaft 4. The worm gear or broken cam 22 is of peculiar formation and comprises an oblique thread 24 set at an angle like a screw 5 thread, and a coöperating thread 25 which is not oblique but lies in a plane perpendicular to the axis of rotation, said two threads at their approaching ends being preferably the distance of one tooth apart, as clearly shown 10 in Fig. 5, and at their divergent ends being apart the distance of a plurality of teeth, herein shown as two teeth. The pitch of the thread 24 depends upon the smoothness and speed of feeding movement desired. The 15 thread 25 serves to positively lock the machine during the snipping operation, as it is necessary that no variation or uncertainty be possible during this delicate and important operation of the machine, and the thread or 20 tooth 24 accomplishes the feeding operation. Accordingly for lack of better terms I will call the vertical tooth 25 the locking tooth or thread, and the oblique tooth 24 the feeding tooth or thread. In the present machine 25 the arrangement is such that the feeding and the halting are timed equally, and hence the vertical tooth extends half way around the shaft and the oblique or feeding tooth extends similarly half way around on the opposite 30 side of the shaft, it being understood that these proportions will be varied accordingly to the variations in the relative timing of the feeding and halting operations. On the same shaft 21 I have shown a cam 26 whose 35 peripheral shape is clearly shown in dotted lines in Fig. 1, said cam being in position to engage a roll 27 on a laterally projecting arm 28 fast at 29 on a rock-shaft 30, provided at its forward end with a bifurcated crank 31 40 which reciprocates a snipping plunger 32 having a long sliding bearing at 33 in the frame of the machine and provided at its upper end with a snipping knife 34. Said rock-shaft 30 is held under normal tendency 45 to maintain constant engagement with the cam 26 by a spring 35 fast at one end on the frame of the machine and at the other end to a pin 36 on the shaft 30, and is normally held in raised position by a dog 37 in engagement 50 with a stop 38, fast on the shaft 30, said dog 37 being held in its normal position by a spring 39 engaging an upright arm 40 at the outer end of the shaft and being operated by a lever 41 and treadle rod 42 (partly not 55 shown). The cam 26 is so shaped and placed with relation to the threads 24, 25 that its entire rocking effect on said rock-shaft takes place during the engagement of the locking tooth or thread 25 with the driving gear 23 60 and hence during the stationary period of the machine, the cam having a circular periphery for the greater portion of its extent excepting at a portion of one side, as indi-

cated at 43, Fig. 1. I prefer this construction because it gives the quick incisive cutting movement which I have found accomplishes the best results.

To permit the snipping at the extreme edge of the work or of the cement applying line, feed wheel 11 is annularly cut away at 70 one side as clearly shown at 44, to accommodate the snipping knife 34, and its overhanging periphery is slotted at 45 at proper intervals to coöperate with the cement applier 7 for the snipping operation. The cement 75 applying wheel 7 is specially constructed with a cellular periphery in order to deliver the cement in the desired thin layer and maintain a uniform and even feed thereof by having three ribs 46, 47, 48 spanned by 80 cross barriers 49 thereby providing two series of pockets 50, 51, the latter being in vertical alinement with the overhanging or snipping portion of the feed roll 11 and having coöperating cutting grooves 52, to receive the cutting edge of the snipping knife 34. These grooves extend into the bottom 85 of the pockets 51 sufficiently to insure a perfect incision in the leather, the corners 53 of the rib 48 being rounded for coöperating to 90 the best advantage in facilitating the entrance of the knife. The barriers 49 or transverse walls extend entirely across the cement-applying wheel 7 to the ribs 48, thereby making complete pockets 51. It 95 will be understood that the showing in Fig. 4 is grossly exaggerated, the knife-receiving slits or openings 52 being only sufficient in size to receive the cutting edge of the knife, and the width of the wheel being in practice 100 usually less than a third of an inch in width for cementing shoe uppers. The desired minimum amount of cement is maintained by scrapers or pads 54, clamps 55, etc., as explained more at length in my copending 105 application, where the construction is claimed, and therefore not explained or shown in further detail in the present case.

Power is applied by any suitable means, herein shown as a belt pulley 56 and belt 57, 110 loosely mounted on the shaft 21 and adapted to move into clutching engagement with a friction flange 58 against a spring 59 by a lever 60 projecting upwardly from a rock-shaft 61 operated by an arm 62 and treadle 115 (not shown) connected thereto at 63.

In use the operator, having started the machine by depressing the treadle arm 62, places the work between the feed wheel 11 and the cement applier 7, guiding the edge 120 of the work in line with the rib 48 and thereby applying the cement in a narrow strip to the edge of the work as required. The work feeds rapidly and to the casual observer continuously, the step-by-step movement being 125 so deftly and rapidly accomplished by the

alternate engagement of the locking tooth or thread 24 and the feeding tooth or thread 25 with the drive wheel 23 that the work proceeds with despatch and yet during the 5 intervals of rest there is an absolute and positive halting of the work, the locking device 24 making it absolutely impossible for the parts to move by momentum or in any other way to get out of absolutely true 10 and accurate position. When a curve in the work is reached the operator instantly depresses the treadle rod 42, thereby disengaging the dog 37 from the stop arm 38 of the snipping shaft 30 so that immediately the 15 cam 26 and spring 35 cause the crank arm 28 to rise and fall, thereby producing an opposite movement in the snipping rod 32, so that each time the crank arm 28 is permitted to fall the snipping knife instantly 20 moves upwardly with a quick snipping movement through the opposite slit 45 into the cutting groove 52 of the cement applicer, said cement applicer and feed wheel 11 being for the instant held stationary and locked by 25 the locking tooth or thread 24. This snipping operation is repeated at each halt of the feed wheel 11 and cement applicer 7 as long as the operator keeps his foot upon the snip-controlling treadle. As soon as the curve 30 in the work has been snipped and a further straight piece of cementing is to be accomplished, the operator lifts his foot from the snip-controlling treadle, thereby permitting the dog 37 to engage beneath the stop arm 35 38 and stop the further operation of the snipping mechanism, the feeding of the work and cementing thereby, however, continuing without interruption until another curvature has to be snipped. In this manner the 40 work proceeds rapidly, the snipping taking place entirely at the will of the operator for a long or short duration, as required.

I have already explained that my invention is capable of a wide variety of changes 45 in its details of embodiment, and accordingly I wish it understood that I intend certain of the claims hereinafter to cover my invention broadly considered. The snipping mechanism *per se* is reserved for a separate application, and is here claimed only in combination 50 with the cementing mechanism.

Having described my invention, what I claim as new and desire to secure by Letters Patent is,

55 1. The combination with cement-applying means and snipping means, of step-by-step operating mechanisms therefor, including means for actuating the snipping means in the intervals of rest of the cement-applying 60 means.

2. The combination with cement-applying means, means uniting therewith to constitute mechanism for feeding the stock to be ce-

mented, and snipping means, of operating mechanisms, including means for positively 65 halting and locking the feeding of the stock during the snipping operation and means for actuating the snipping means during the halting of the stock.

3. The combination with cement-applying 70 means, means coöperating therewith in feeding the stock, and step-by-step operating mechanism for said two means, of snipping mechanism arranged to engage the stock on the opposite side to that receiving the cement. 75

4. The combination with a cement applicer and a work feeder, of snipping mechanism arranged to move through said work feeder toward said cement applicer for snipping the 80 work, and operating means for actuating said snipping mechanism.

5. A machine, comprising a cement-applying wheel, provided with a series of knife grooves, means for supporting the work, a 85 snipping knife, and operating mechanism for the latter constructed and arranged to move said snipping knife through the stock in co-operation with said knife grooves.

6. A machine, comprising a cement-applying 90 wheel, a feed wheel adapted to receive and feed the stock against said cement wheel, and snipping mechanism, including a knife located at said feed wheel and constructed and arranged to move into engagement with 95 said cement wheel for snipping the work.

7. A machine, comprising cement-applying means, feeding mechanism coöperating therewith to feed the stock to be cemented, snipping mechanism, and operating mechanisms for the aforesaid parts, including a drive gear, and means for operating the same step-by-step, consisting of a vertical segmental locking tooth and an oblique segmental feeding tooth to engage said drive gear. 100 105

8. A machine, comprising cement-applying means, including a rotary wheel having peripheral pockets formed by peripheral ribs and transverse barrier plates, and snipping means including a knife coöperating with 110 said wheel, the latter having shallow slits for receiving said knife.

9. A machine, comprising cement-applying means, including a rotary wheel having peripheral pockets formed by peripheral ribs 115 and transverse barrier plates, and snipping means including a knife coöperating with said wheel, the latter having shallow slits with rounded edges for receiving said knife.

10. A machine, comprising a cement-applying wheel, a snipping knife coöperating therewith, means for rotating said wheel and means to reciprocate said snipping knife 120 radially of said wheel.

11. A machine, comprising a cement-applying wheel, a snipping knife coöperating 125

therewith, and operating mechanisms constructed and arranged to alternately rotate said wheel and reciprocate said knife.

12. A machine, comprising a cement-appling wheel, a snipping knife coöperating therewith, means for rotating said wheel step-by-step, a slotted work feeder, means to operate said work feeder step by step simultaneously with the rotation of said wheel, and means for reciprocating said knife

through a slit of said work feeder, to snip the stock, in the interval of rest of said work feeder and wheel.

In testimony whereof, I have signed my name to this specification, in the presence of 15 two subscribing witnesses.

HARRY I. ILLINGWORTH.
